UNITED STATES PATENT OFFICE.

MORRIS L. SILVERSTEIN, OF LAWRENCE, MASSACHUSETTS.

DETACHABLE LEATHER HEEL.

965,415.

Specification of Letters Patent. Patented July 26, 1910.

Application filed November 18, 1908, Serial No. 463,272. Renewed January 24, 1910. Serial No. 539,879.

To all whom it may concern:

Be it known that I, MORRIS L. SILVERSTEIN, a citizen of the United States, residing at Lawrence, in the county of Essex and State of Massachusetts, have invented new and useful Improvements in Detachable Leather Heels, of which the following is a specification.

This invention relates to the class of boots and shoes, and more particularly to detachable heels, and has for an object to provide a heel of this character that can be conveniently attached to the shoe so that when the lower portion of the heel is run down or worn it can be replaced by a new portion at a relatively low figure and by those unfamiliar with the art of shoe making.

A further object of this invention is to provide a threaded connection between the detachable portion of the heel and the permanent part thereof, and to provide novel and efficient means for preventing rotation of the detachable portion.

Other objects and advantages will be apparent as the nature of the invention is better disclosed and it will be understood that changes within the scope of the claim may be resorted to without departing from the spirit of the invention.

In the drawings forming a portion of this specification and in which like numerals of reference indicate similar parts in the several views, Figure 1 is a sectional view taken longitudinally through a portion of a shoe showing the application of the detachable heel. Fig. 2 is a fragmentary perspective view of the threaded connections or elements. Fig. 3 is a fragmentary perspective view of the improvements for preventing rotation of the detachable heel.

Referring now more particularly to the drawings, there is shown a shoe 1 which may be of any suitable form, and which is provided with a heel portion 2 permanently secured in any suitable manner to the body portion of the shoe, and which has embedded therein a connection or element 3 comprising a plate 4 having formed therein a plurality of passages 5 for the reception of suitable fastening devices which may be engaged with the shoe. The plate has depending therefrom a cylindrical socket member 6 in which is formed a vertically disposed

threaded passage 7. A detachable heel is illustrated at 8 and has embedded therein a connection 9 comprising a plate 10 having passages 11 formed therein, for receiving suitable fastening devices as will be readily understood. The plate 10 is provided with a centrally located vertically extending threaded pin 12.

From the construction herein set forth and described it will be seen that the heel 8 may be conveniently engaged with or disengaged from the portion 2 previously referred to so that when the portion 8 is run down or worn it may be replaced by a new heel section at a minimum figure and by those unskilled in the art of shoe making.

At the front, the heel 8 is provided with a depression 13, and a similar depression 14 is formed in the front of the portion 2, and the said depression 13 is thus adapted to lie with the depression 14 to form a substantially hemispherical concavity. The portion 2 is provided with a threaded stud 15 having a rearwardly directed flattened head 16 which is perforated at 17 so that the said stud 15 may be conveniently held to the portion 2 of the heel. The stud is thus such that it projects into the recess 14 formed in the said portion 2, and is adapted to receive a nut 18 having a substantially hemispherical shaped portion 19 to fit the concavity formed by the depressions 13 and 14. The nut 18 is preferably provided with wrench engaging faces 20, and alining kerfs 21 adapted to receive a screw driver or the like in driving the nut into the concavity. It will be seen that the stud 16 and the nut 18 provide effective means for preventing rotation of the detachable heel. When it is desired to substitute a new part 8 for a worn part, the nut 18 is removed so that the part 8 can be conveniently revolved to disengage the pin 12 from the passage 7.

I claim:

The combination with a shoe having a heel portion having secured thereto a rearwardly directed stud having a flattened head portion engaged with the said heel portion, said stud having its threaded portion extending forwardly beyond the front edge of said heel portion, an interiorly threaded socket member carried by the heel portion, of a detachable heel having embedded there-

in a vertically disposed threaded stud engaged with the interiorly threaded socket member, said heel portion having a concavity formed therein, said detachable heel 5 having a concavity formed therein to align with the concavity formed in the heel portion, and a nut engaged with the threaded stud provided with a hemispherical portion adapted to frictionally bind against the

walls of the concavities formed in the heel 10 portion and in the said detachable heel.

In testimony whereof I affix my signature in presence of two witnesses.

MORRIS L. SILVERSTEIN.
